FIGURE 1 is a perspective view of a case for a portable recorder or similar article embodying my new design, with the top cover in a closed position;

FIGURE 2 is a plan view of the case for a portable recorder as shown in FIGURE 1;

FIGURE 3 is a rear view of the case for a portable recorder as shown in FIGURE 1;

FIGURE 4 is a right side view of the case for a portable recorder, as shown in FIGURE 1;

FIGURE 5 is a bottom view of the case for a portable recorder as shown in FIGURE 1;

FIGURE 6 is a front view of a case for a portable recorder as shown in FIGURE 1;

FIGURE 7 is a perspective view similar to FIGURE 1, with the top cover in an open position;

FIGURE 8 is a plan view of the case for a portable recorder as shown in FIGURE 7;

FIGURE 9 is a rear view of the case for a portable recorder as shown in FIGURE 7;

FIGURE 10 is a right side view of the case for a portable recorder as shown in FIGURE 7;

FIGURE 11 is a bottom view of the case for a portable recorder as shown in FIGURE 10;

FIGURE 12 is a front view of a case for a portable recorder, as shown in FIGURE 10.

The broken line showing of a representative recorder mechanism which appears in FIGURES 7, 8, 10 and 12 is for illustrative purposes only.

The dominant features of my new design are shown in solid lines in the drawing.

This application is a continuation-in-part of applicant's co-pending application, Ser. No. D637, filed Jan. 17, 1966, and now abandoned.

I claim:

The ornamental design for a case for a portable recorder or similar article, substantially as shown and described.
